UNITED STATES PATENT OFFICE.

CHARLES R. WEEDE, OF WALTON, KANSAS.

GARMENT OR SHOE FASTENER.

1,218,499.

Specification of Letters Patent. Patented Mar. 6, 1917.

Application filed May 5, 1916. Serial No. 95,646.

To all whom it may concern:

Be it known that I, CHARLES R. WEEDE, a citizen of the United States, residing at Walton, in the county of Harvey and State 5 of Kansas, have invented new and useful Improvements in Garment or Shoe Fasteners, of which the following is a specification:

The invention relates to fasteners, and more particularly to the class of garment or 10 shoe fasteners.

The primary object of the invention is the provision of a fastener wherein the openings in a garment, shoe upper, corset or the like can be closed and fastened in a quick 15 and convenient manner, without the necessity of the use of buttons, hooks, elastic webbing, lacing or other like devices usually employed for this purpose.

Another object of the invention is the provision of a fastener of this character wherein the construction thereof is novel in form so as to render it practical and reliable as well as assuring the effective fastening of the garment, shoe, corset or the like with 25 despatch.

A further object of the invention is the provision of a fastener of this character which is simple in construction, thoroughly reliable and efficient in its purpose, strong, 30 durable and readily and easily manipulated and inexpensive in manufacture and installation.

Other objects will be in part obvious and in part hereinafter set forth.

The invention accordingly consists in the features of construction, combination of elements and arrangement of parts which will be exemplified in the construction herein-after described, and the scope of the application of which will be indicated in the appended claim.

In the accompanying drawings:

Figure 1 is a fragmentary plan view of a portion of a garment showing an opening with the fastener constructed in accordance with the invention applied to parts adjacent each other of the garment for closing the gap therebetween and the covering for the fastener removed;

Fig. 2 is a sectional view on the line 2—2 of Fig. 1;

Fig. 3 is a sectional view on the line 3—3 of Fig. 1;

Fig. 4 is a plan view of one part of the runner.

Similar reference characters indicate cor-

responding parts throughout the several views of the drawing.

Referring to the drawings in detail, A designates generally a portion of a garment; 60 b and c the parts of the garment separated from each other to provide a closing gap therebetween, and this gap or opening accommodates the fastener hereinafter fully described.

The fastener comprises two rows of keepers B, the keepers in each row being arranged in series and each including outer and inner plates 5 and 6 respectively which are fastened in place against opposite faces 70 of each part of the garment at the edges adjacent each other. These plates 5 and 6 are constructed from a single strip of material bent on itself to form a substantially arrow shaped socket 7 which extends inwardly between outwardly bulged portions 8 bent from the plates 5 and 6, as shown, for detachable engagement therewith of a runner or slide C hereinafter fully described. Alternate outer plates 5 of the 80 series constituting each row are formed with slots 9, through which engage sleeve-like tongues 10 formed on the remaining outer plate of said series, and in this manner the keepers are hinged or flexibly connected together.

The slide or runner C comprises a series of plates 11 each formed at opposite ends with knobs or heads 12 which are shaped in cross section correspondingly to the shape 90 of the socket 7 and gradually taper in reverse directions toward opposite ends so as to freely pass through the sockets 7 in the keepers B when the slide or runner C is moved in the gap between the parts b and c of the garment for the fastening thereof and the closing of the gap or opening between the edges of said parts adjacent each other.

The plates 11 are formed with medial tongues and slots 13 and 14 respectively, the slots being adapted to receive the tongues which, at their ends, are bent to form sleeve-like extremities 15 for hinging 100 or flexibly connecting the plates 11 to each other. The outermost or end plates 11 of the slide or runner C are formed with suitable loops 16 which provide hand tabs for the adjustment of the slide or runner in the opening or closing of the gap between the parts b and c of the garment. The keepers B and the runner or slide C are preferably 105 110

covered on each of their sides, as at 17, by the use of canvas or cloth material of sufficient thickness to stiffen the same so as to avoid undue flexing thereof and also to provide means whereby the keepers B may be sewed or attached to the respective edges *a* and *b* of the garment. The covering on the slide or runner C permits the user to surface the covering with suitable cloth to match the cloth of the garment. The keepers B at opposite ends are formed with tabs 18 which serve as hand holds for the operator of the slide or runner C, as will be obvious.

15 From the foregoing description, taken in connection with the accompanying drawings, the construction and manner of use of the herein described fastener will be readily apparent and, therefore, a more extended 20 explanation has been omitted.

Having thus described my invention, I claim:

A fastener of the character described comprising a plurality of keepers, each formed from a single piece of material bent 25 to provide outer and inner plates and a socket extension which protrudes inwardly, the plates being bulged at opposite sides of the socket for accommodating the same, alternate outer plates being formed with slots, 30 tongues formed on the remaining outer plates and engaged in the slots for hingedly connecting the same, a slide runner including a series of plates, each formed with a knob correspondingly shaped to the socket 35 and adapted for slidable engagement therein, and extensions on the last named plates for hinging the same to each other.

In testimony whereof I affix my signature.
CHARLES R. WEEDE.

Copies of this patent may be obtained for five cents each, by addressing the "Commissioner of Patents, Washington, D. C."
